METHOD OF SEALING PACKAGES

Samuel Bergstein, Cincinnati, Ohio

Application August 12, 1932, Serial No. 628,566

7 Claims. (Cl. 93—6)

My invention relates to methods of sealing packages in order to make the packages substantially sift-proof and substantially hermetically sealed.

5 In the art there has been considerable development in different methods of making cartons, containers and the like substantially hermetically sealed. In my co-pending application, Serial No. 603,064, filed April 4, 1932, I have described a method of hermetically sealing packages of the type in which overlapped wall portions form closures for the ends of the packages, with a juncture exposed along a wall lying at an angle to said overlapped wall, which consists in applying a coating of a hermetically sealing liquid to an exposed edge juncture of overlapped walls adjacent a wall lying at an angle thereto, and thereafter scraping off any excess of liquid from the wall and said juncture.

20 While the method suggested in my copending application, to which reference has been made, is completely successful in the hermetic seal which it provides, it requires ordinarily an extra manufacturing operation which has certain disadvantages.

In ordinary sealing of cartons and containers, it is usual to move cartons, after being squared up, vertically, with the open ends up and down, and with the two opposite longer panels being 30 parallel with the machine, through the sealing apparatus, which apparatus first effects a seal on the bottom of the carton by first folding the end sealing flaps of the two narrow or front and back walls, thereafter applying adhesive to one 35 of the end sealing flaps of one of the wide panels, folds same over to effect an adhesion between the first two folded sealing flaps and the last named sealing flap. Thereafter applying adhesive to the remaining wide end sealing flap 40 to bring about adhesion between the two opposite wide end sealing flaps.

The carton then, with the bottom sealed, is usually moved to the filling machine, where the contents are inserted into the carton, there- 45 after it is conveyed and brought in contact with the mechanism that closes the top of said carton, in a similar manner as described above for the bottom.

By means of adjustable scrapers acting upon 50 the glue wheel, it is possible and necessary to regulate the amount of adhesive the glue wheel carries and it is usually the practice to deposit a thin film of adhesive on the sealing flaps, so as to bring about an effective adhesion between 55 the sealing flaps in as quick a time as possible.

By this means, there is no difficulty in securing a proper closure or seal but it is impossible to secure a sift-proof or vermin-proof condition, due to the fact that, on all the corners, there remain small openings or pinholes, which permit powders to sift through or vermin to pass in, and to prevent this, it is the usual practice to either first insert such powdered contents into a bag and, thereafter, place it into a carton or to wrap the carton after the contents are in it 60 and sealed.

It is the object of my invention to provide a method of effecting a hermetical seal and thus avoid the necessary labor and material that are being used now to secure a sift-proof container, 70 by means of (when applying the adhesive to the sealing flaps) a recess cut into the scraper permitting a heavy bead of glue to be carried on that portion of the glue wheel that will deposit this heavy bead over the score line where the wide 75 sealing flaps are articulated to the main body of the carton, the remaining glue flaps having the usual thin film of adhesive and, after these panels are folded over, the excessive adhesive on these score lines fills effectively the small corner 80 openings.

There are several ways of carrying out my proposed new method, and in the drawing I have illustrated diagrammatically several proposed arrangements which will be found effective.

In the drawing:

Figure 1 is a diagrammatic representation in perspective of a container having the adhesive applied to its side closing flaps.

Fig. 2 shows diagrammatically a detail of a 90 modification of the manner of applying the adhesive to the closure flaps of a carton over that shown in Fig. 1.

Fig. 3 shows a detail plan view of the adhesive applying rolls shown in Fig. 1.

Fig. 4 is an end elevation of the carton illustrated in Fig. 1, after the adhesive has been applied to it.

Fig. 5 shows a sealed container sealed in accordance with my invention.

Referring first to Fig. 1, I have shown the conveyor belts 1, on which the carton indicated at 2 may be fed along. The end closure flaps 3 and 4 have at that stage of the adhesive applying operation illustrated, been folded in at right angles to the end and side walls of the box. The side walls of the box are indicated at 5. The side closure flaps of the container or carton are indicated at 6, 7, and subsequent to the application of the adhesive to the inner surfaces of the flaps 6 and 7, 110

flap 7 is folded in first, and then flap 6 is laid on top of it. The mechanism for performing these folding operations is so old and well known that it is not thought that a specific description of such mechanism is needed. The adhesive applying mechanism diagrammatically shown in Fig. 1 has glue pans 8, 9, in which glue feed rolls 10, 11, respectively, rotate, said glue rolls being preferably mounted on a single shaft such as that indicated at 12.

The two intermediate wheel rolls 13 and 14, are positioned between the two glue feed rolls 10 and 11, and the applying rolls 15 and 16, and are adjustable in relation to the glue feed rolls 10 and 15. These rolls 13 and 14 perform two distinct functions. They carry the glue from the rolls 10 and 11 to the rolls 15 and 16, and also by their adjustability, control the amount of glue passing over them to rolls 15 and 16. If the rolls 13 and 14 are adjusted closely to the rolls 10 and 11, the film of glue passing through the rolls and on to the applying rolls 15 and 16 will be thin, while if these rolls 13 and 14 are adjusted away from the rolls 10 and 11 the film of glue will be relatively thick. It therefore can be readily seen that if there is any depression or cut out portion in the rolls 13 and 14, the glue carried through the rolls on that portion will be thicker than the glue carried through on the rest of the roll.

30 The adhesive applying rollers 15, 16 are those which actually supply the adhesive to the surfaces of the sealing flaps of the carton.

By notching the rollers 13, 14 as indicated at 17, 18, a thicker layer of adhesive in the form of 35 a narrow band 19 is formed at such suitable distance from the articulated corner edges of the side flaps 6 and 7, that narrow bands of adhesive 20 are applied substantially along the lines of articulation of the container.

40 Referring to Fig. 4, the side closure flaps 6, 7 are clearly illustrated, with a thin coating 21 of adhesive applied to the upper surfaces of the flaps. The narrow band of supercoated adhesive is indicated at 20.

45 When the side flaps 6 and 7 are folded in to the position illustrated in Fig. 5, small beads such as are indicated at 22 in Fig. 5 are formed at the corner edges so that the usual pin point openings are hermetically sealed.

50 In Fig. 2 I have illustrated an alternate construction in which the glue pan is indicated at 8a. A take-off roller 13a peripherally engages the surfaces of the adhesive feed roll 10a, and a layer of adhesive is carried by the roller 13a into contact with the surface of the applying roller 15a, which engages the surfaces of the closing flaps of the carton.

55 In order to articulate the thickness of the adhesive on the rollers 15a I have shown a scraper 60 knife 23, adjustably mounted in a support 24 and having a recess 25, which will permit an unusually thick band of adhesive to pass around on the roll 10a. This adhesive with the narrow band is carried by the take-off roller 13a to the applying roller 15a. The take-off roller 13a has a narrow groove 17a so positioned as to register with the narrow band formed on the roll 10a by the scraper and the aperture 25. This groove prevents the take-off roll 13a from flattening out the band formed on the roll 10a. This modification forms the same narrow band in the adhesive on the applying roll, as before described, and causes the narrow bead of adhesive to be formed at the 70 corner edges of the carton, which effectively 75

forms of the closure flap a hermetic seal for the carton.

The adhesive must necessarily be in a semi-liquid state to make it possible for the glue wheels to spread the glue evenly in as thin a film as possible. The adhesive being in semi-liquid form, contains a relatively high proportion of water, and before the adhesion takes place the moisture in the adhesive must be absorbed in the fibers of the carton material.

80 When cartons are being sealed at the rate of 40 to 80 or more per minute, in order to make it possible to handle these cartons so that they may be removed from the machine, it does not allow maintaining pressure or contact against the sealing flaps but for a very brief period. Hence, the adhesion must take effect as soon as possible and it is for that reason that a thin film of adhesive is necessary to be applied, as the less adhesive is applied, the quicker the adhesion 85 between the sealing flaps will be effected. The narrow stripe of the thicker layer of adhesive will not set or dry as quickly as the remaining portion, but that does not prevent the handling or removing of the cartons from the machine, for 90 the reason that the sealing flaps have been effectively sealed between the surfaces where the thin film was deposited and the bead of adhesive, #20, thereafter, has ample time to dry or set, even 95 after these cartons have been packed in shipping 100 cases, without in any way effecting the purpose for which the bead of adhesive has been applied.

105 The rolls 13 and 14 and the scraper knife 23 are adjustably mounted so that the narrow stripes of adhesive which form the corner closures may 110 be adjusted to various widths of cartons.

115 By tests made with cartons sealed in accordance with the invention described herein it is unnecessary to further wrap the packages, as with wax paper, or to carry out the steps of my process described in my co-pending application, Serial No. 603,064, and a sift-proof package which is substantially hermetically sealed may thereby be formed.

Having thus described my invention, what I 120 claim as new and desire to secure by Letters Patent, is:—

1. The method of sealing the closure flaps of 125 cartons which consists in applying thin coatings of adhesive to the contact surfaces of opposed pairs of closure flaps with thicker stripes of adhesive applied along the lines of articulation of the closure flaps and the carton walls, and then folding over the closure flaps to superposed position, one on the other, whereby a bead of adhesive 130 is formed at the corner edges of the under surface of the closure flaps.

2. The method of sealing cartons having end 135 and side closure flaps, which consists in folding in the end closure flaps, applying adhesive in a thin layer to the contact surfaces of the side closure flaps, leaving a thicker band along each of the lines of articulation of said closure flaps, then folding said side closure flaps into overlapping relation, thereby causing the adhesive 140 from the thicker bands to exude along the under surface of the side closure flaps forming hermetically sealing masses of adhesive at said corner edges.

3. The method of hermetically sealing the 145 corners of the closure flaps of cartons, which consists in applying excessive adhesive to portions of the closure flaps so that when they are folded down beads of adhesive will be forced into the corners, which when dry, will hermetically seal 150

10 said corners and then folding down the flaps and securing them in folded down condition.

15 4. A process of sealing the closure portions of containers adhesively, which comprises applying adhesive upon the surface of a closure portion in a thin layer to permit rapid adhesion and setting, and also applying adhesive thickly to a selected part of the surface of a closure portion whereby said thick application of adhesive is enabled to seal, by filling, a crevice formed by the interengagement of said closure portions.

20 5. The method of insuring sealed closure of the crevices left in the corners of a carton at the ends of its flap folds, which flaps are provided with means for holding said flaps in folded closed condition, consisting in applying adjacent to the flap folds a sealing substance in such greater quantity than would be proper for adhesion of the flaps, and of such consistency, as to squeeze into said crevices incident to the folding of said flaps into folded closed condition, and then folding said flaps into said condition and holding said flaps in said condition by said holding means, whereby said substance may assume a permanent sealing relation to said crevices while held by the folded and held flaps.

25 6. The method of insuring sealed closure of the crevices left at the corners of a carton at the ends of its flap folds, which consists in providing said flaps with means for holding them in folded closed condition which becomes effective in the course of rapid machine folding and closing of the flaps, and providing adjacent to

30 the flap folds a sealing medium in such greater quantity than would be proper for adhesion of the flaps, and of such consistency, as to squeeze into said crevices incident to the folding and closing of the flaps, and then folding and closing the flaps and causing said holding means to become effective as aforesaid, whereby said sealing medium may assume a permanent sealing relation to said crevices while held by the folded and held flaps during a period of time exceeding that required for the rapid machine folding and closing of said flaps.

35 7. The method of sealing the crevices at the corners of a carton, at the ends of its flap folds, independently of any lining element which the carton may have, which consists in providing sealing substance interiorly of the carton flaps in such greater quantity than would be proper for adhesion of the flaps and of such consistency and so located as to be squeezed into said crevices incident to folding and closure of the flaps, and additionally providing for holding the flaps in their folded and closed condition by means effective in the course of rapid machine operation, folding and closing said flaps by said operation and thereby causing said holding means to become effective as aforesaid, and allowing said sealing substance to assume a permanent sealing relation to said crevices while held by the folded and held flaps during a period of time exceeding that required for the rapid machine folding and closing of the flaps.
